METHOD OF AND MECHANISM FOR TYING KNOTS

Harry G. Lind, Rockford, Ill., assignor to Barber-Colman Company, Rockford, Ill., a corporation of Illinois

Application June 7, 1939, Serial No. 277,755

20 Claims. (Cl. 289—1)

The invention relates to an improved method of and apparatus for tying knots, and more particularly, for uniting threads or strands of such material as woolen yarn.

In some aspects the present invention may be considered as an improvement upon the knot-tying method and apparatus disclosed in Burt A. Peterson Patent No. 1,657,407 issued January 24, 1928 in which a pair of threads are united by a so-called weaver's knot.

A weaver's knot has been found to be well adapted to the permanent uniting of the ends of cotton threads or yarn. In the case of wool, however, a weaver's knot is likely to become untied, and it is therefore the general object of the present invention to provide a method of and mechanism for tying knots which, while not limited to use with woolen yarns, is capable of firmly and permanently uniting yarns of such material.

More specifically, it is an object of the invention to provide a method of and mechanism for tying together a pair of threads by means of a novel form of knot, which is somewhat related in form to a weaver's knot, but which embodies variations in the configuration and relative positions of the threads such that the threads are firmly interlocked and held together even though made of such materials as wool.

Further objects and advantages of the invention will become apparent as the following description proceeds, taken in connection with the accompanying drawings in which:

Figure 1 shows a completed knot of novel form made in accordance with the improved method of knot tying herein disclosed.

Fig. 1^a shows the loop formation of the threads before the knot of Fig. 1 is drawn tight and completed.

Fig. 1^b shows the configuration of the threads intermediate the steps of Figs. 1^a and 1, respectively.

Fig. 2 is a side elevation of a knotter mechanism embodying the invention. Parts moving to the right in this view are hereinafter referred to as moving "outwardly."

Figs. 3 and 4 are, respectively, enlarged detail end and plan views (partly in section along the lines 3—3 and 4—4, respectively, in Figs. 2 and 3) of the mechanism for actuating the knotter post.

Fig. 5 is an enlarged detail bottom plan view of one of the thread clamps of the knotter mechanism.

Figs. 5^a, 5^b and 5^c are stop motion views similar to Fig. 5 showing successive steps in the operation of the parts illustrated.

Fig. 6 is a fragmentary detail view of part of the mechanism of Fig. 5.

Fig. 7 is an enlarged detail perspective view of the slack take-up mechanism included in the knotter.

Figs. 8 to 12, inclusive, are fragmentary perspective views of the knotter mechanism showing successive steps in the knot tying operation.

Fig. 13 is a time chart illustrating the sequence of operations of the various mechanisms by the controlling cam.

Referring more particularly to the drawings, Fig. 1 shows a completed knot uniting a pair of threads *a* and *b*. For purposes of exemplification only, it will be assumed that thread *a* is a reserve thread leading from a bobbin in a winding machine and that thread *b* is an exhausted thread on a cheese or yarn mass which is being wound in the machine. To make more readily discernible the convolutions of the two threads *a* and *b*, these threads have been shown in the drawings as white and black, respectively. The knot of Fig. 1 is of novel form and has been found capable of firmly and permanently uniting woolen threads. It is referred to herein as a doubly interlocked knot.

To better understand the configuration of the threads *a* and *b* in the doubly interlocked knot of Fig. 1, reference should be made to Fig. 1^a. In this figure the threads are shown before they are finally drawn tight to complete the knot. In Fig. 1^a, the threads *a* and *b* are looped in what, for purposes of explanation and analysis, may conveniently be termed a modification of a loose weaver's knot. A weaver's knot as such is, of course, a well recognized standard knot, and as to it, reference may be made, for example, to Fig. 29 of said Peterson patent referred to above.

Upon a comparison of a weaver's knot with that of Fig. 1^a herein it will be seen that the two are alike in that, first, there are oppositely extending loops *a*₁ and *b*₁ in the end portions of the respective threads *a* and *b*, second, the standing part *a*₂ of one thread *a*, extends through the loop *b*₁ in the other thread *b*, and third, the standing part *b*₂ and end *b*₃ of the other thread *b* extend side by side through the loop *a*₁ in the first thread *a*. The knot of Fig. 1^a differs from a standard weaver's knot, however, in that the end *a*₃ of the first thread *a* is not clamped between the standing part of the thread *a* and the opposed portions of the standing part *b*₂ and end *b*₃ of the other thread *b*, but is, on the other hand, twisted about the standing part *a*₂ of the thread *a* and thrust outwardly from the remain-

der of the stands. By virtue of this difference in configuration of the strands it is possible finally to draw the knot tight in a manner which will hereinafter appear, so as to form the strong and durable doubly interlocked knot of Fig. 1.

In accordance with one aspect of the present invention the threads to be united are preliminarily looped in a somewhat loose form with the strands arranged as shown in Fig. 1^a in what is termed herein a modified form of weaver's knot. Then, to complete the novel knot of Fig. 1, the twisted portion of one of the threads (shown in Fig. 1^a at *a*₄) is pulled through the loop of the other thread (shown as *b*₁) as an incident to drawing the knot tight (Fig. 1^b). In this way the loop *b*₁, in the thread *b*, encircles and firmly clamps the twisted portion *a*₄, of the thread *a*, against the standing part *a*₂ of the thread *a*. In general, the strands are so interwoven or interlocked that an extremely strong and firm knot is formed even though the strands or threads be made of wool.

In carrying out the present invention the preliminary looping of the threads in the form of a modified weaver's knot such, for example, as that shown in Fig. 1^a, is preferably accomplished by means of a novel method of knot tying herein disclosed. Generally stated, this method comprises (see Figs. 8 to 12), seizing a bight in one of the threads (such as the thread *a*) to form a main loop. The loop is then made into what may be termed a "doubly twisted" loop by twisting the thread at the base of the loop about itself through substantially a turn and a half at the base of the loop (see Fig. 8). Then a bight of the same thread, adjacent the main loop is drawn through the loop to form a temporary second loop. Thereupon a second thread (such as the thread *b*) is inserted through the second loop thus formed, and the second loop subsequently withdrawn from the main loop, together with the inserted thread, thereby forming a third loop encircling one of the standing parts of the thread having the main loop in it. In the course of this withdrawal operation the second or temporary loop is dissolved. By manipulating the threads in this manner the formation of the initial main loop forms, for example, the final loop *a*₁ in the thread *a* and leaves this thread twisted at the base of the loop as shown at *a*₄. Similarly, the third loop, so-called above, is represented in Fig. 1^a by the loop *b*₁ in the second thread *b*. Having thus preliminarily arranged the threads as shown in Fig. 1^a, they may then be pulled tight into the form of Fig. 1^b and then Fig. 1, as previously described.

The novel knotter mechanism herein disclosed, for carrying out the knotting method outlined above, is basically similar to that disclosed in said Peterson patent. Accordingly, reference may be had to such patent for a general description of the apparatus and for details of parts which are substantially identical. The more detailed portions of the description herein are directed primarily to the differences in construction which make possible the use of the knotter herein disclosed for tying the novel form of doubly interlocked knot of Fig. 1, as distinguished from an ordinary weaver's knot such as is tied by the knotter of said Peterson patent.

Referring now to Fig. 2, the present embodiment of the knotter mechanism is adapted to receive a pair of threads (not shown in Fig. 2) at its outer end for tying them together. For example, one of the threads may be a reserve

thread, that is, one from a reserve bobbin, and the other an exhausted thread end from a cheese or yarn mass in a winding machine. For an example of a winding machine of the type referred to, Howard D. Colman Patent No. 1,267,977

- 5 may be considered. Of the two threads noted, the reserve thread is operated upon first in the present mechanism and, consequently, the manipulations of this thread will be first described.
- 10 The reserve thread is seized at two vertically spaced points, to form a bight between them, by the suction nozzle 9 and a lower clamp 11 (Fig. 2), the loose end of this reserve thread being picked up by the nozzle. After the thread has 15 been looped it is seized and sheared off by an upper clamp 10, the waste end of the thread being drawn off in the suction tube. The upper clamp may be substantially identical with the corresponding clamp in the knotter of said Peterson patent. The actuating mechanism for the lower clamp 11 is, however, of somewhat different form than that of the Peterson knotter in view of the different timing required in the present knotter. Furthermore a slack drawing hook 12, located just above the lower clamp 11, 20 is in the present device arranged to aid in actuating such lower clamp and is combined with other parts in a novel form of tensioning mechanism to exert a tension on the reserve thread, 25 which varies in value at different periods in the knotting operation to match the requirements of the operations used in tying the novel knot herein contemplated. Consequently the lower clamp 11, slack drawing hook 12 and associated 30 thread tensioning parts are described hereinafter in some detail in view of the novel structures involved. In the case of the upper clamp 10 and other such parts which are substantially duplicated from those shown in said Peterson patent, 35 reference may be made to the latter for details of construction.

Generally stated, the upper clamp 10 is a shearing and gripping clamp. It not only grips the end of the thread, but also shears it off neatly 45 adjacent the knot. The lower clamp 11 is, however, simply a gripping, rather than a combined shearing and gripping, clamp. These clamps are actuated in timed relation to each other and to the other parts of the knotter (see time chart 50 Fig. 13). More particularly, at least one and preferably both clamps remain open until the initial looping of the thread has been accomplished (see Fig. 8) in the knotting operation so that sufficient slack will be available for this 55 purpose. During this time the thread is tensioned sufficiently, to stay in place, by the slack drawing hook 12. This hook not only serves to tension the thread but also draws a little additional slack which is released for knotting purposes after the clamps 10 and 11 are closed.

Of primary importance in carrying out the knotting operation is the maintenance of the threads in proper position and under requisite tension. The clamps serve to position the threads for this purpose and the slack hook 12, with its cooperating parts hereinafter described, 65 adjusts the tension in the reserve thread automatically to suit the requirements of successive steps in the knotting operation.

To insure proper timing of the various actuating elements of the knotter mechanism they are all driven from a single rotatable cylindrical cam 13 (Figs. 3 and 4). This cam has suitably contoured individual cam tracks in both its end and side surfaces. The relative timing of the actua-

tion of the different parts may be determined by reference to the time chart, Fig. 13.

The lower clamp 11 for the reserve thread (Fig. 5) embodies a fixed jaw or finger 14 and a co-operating movable jaw or clamping finger 15. 5 The jaw 14 is shown herein as an integral extension on a stationary plate 16 (see Fig. 2 in addition to Fig. 5). Similarly, the movable jaw 15 constitutes an integral extension on a plate 17, which is pivoted on a stud 18 riveted to the stationary plate 16 and is yieldably urged against the bottom face of the latter by a compression spring 19 encircling the stud 18.

As to the actuation of the lower clamp 11 for the reserve thread, initial movement of the swingable clamp jaw 15 from open position (Fig. 5) to an intermediate position in which it is just ready to close (Fig. 5^a) is accomplished in response to a retractive motion of the slack drawing hook 12. In this retractive or inward motion of the hook 12, slack is pulled in the bight of the reserve thread lying between the clamps 10 and 11 so that sufficient thread will be available for forming the doubly twisted loop in the knotting operation.

The slack hook 12 is fashioned on the end of an arm 20, pivoted intermediate its ends at 21 and having a cam follower roller (not shown) on its inner end which is received in a cam track groove on the actuating cam 13. As the slack hook 12 is retracted it pulls a bight of the reserve thread *a* across a projection 23 (Fig. 7) on a plate 24 located at the upper surface of the slack hook. Furthermore, during this retraction of the slack hook 12 a cam plate 25 bolted to the hook arm 20 strikes a pin 26. This pin 26 is carried by a curved link 27, pivoted at its upper end, and passes through a cam slot 28 in the movable clamp jaw plate 17. Accordingly, as the hook arm 20 continues its descent to the position of Fig. 5^a, the pin 26 rides along a cam surface 29 on the cam plate 25 and oscillates the clamp plate 17 from its full open position (Fig. 5) to its intermediate but still open position (Fig. 5^a). In this way the movable clamp jaw 15 is shifted to an intermediate point or position where it is just ready to close during the time that the slack is being drawn for the knot by the slack hook 12. It will be noted that the pin 26 has a flattened side 26^a (Fig. 6) opposed to the cam plate edge 29.

Final closure of the lower clamp 11 is accomplished in response to a lateral shifting of a vertical knotter post 30 (see Fig. 2 as well as Fig. 5) which takes part in the knotting operation. This knotter post is both laterally and axially movable, being substantially identical in form and function with the corresponding part in said Peterson patent noted above. It may be noted here that the post 30 is carried on and shifted laterally by a pivoted arm 31 which is oscillated by the main driving cam 13. To achieve this final closure of the clamp 11 in response to the movement of the knotted post 30, a stud 31^a on the arm 31 which also carries the post 30 is utilized as a pivot for the link 27. Consequently, when the knotter post 30 is shifted laterally (upward as viewed in Fig. 5^a) by the corresponding movement of its supporting arm 31, the stud 31^a pulls up on the link 27 and drags the pin 26 about the nose of the cam plate 25 (Fig. 6). The shift of the post 30 to close the clamp carries the post from the position of Fig. 5^a to that of Fig. 5^b. By thus shifting the pin 26 to the right (as viewed in Fig. 5^a) the clamp jaw plate 17 is oscillated to

its fully closed position (Fig. 5^b). By virtue of this timing the reserve thread *a* can be freely drawn through the lower clamp 11 during the initial looping of the thread in the knotting operation, and in this interval the slack hook 12 is retracted to tension the thread and to draw slack in the bight of the thread. After this slack is drawn the lower clamp 11 is closed to hold the lower end of the bight firmly.

10 For the first step of the looping of reserve thread *a* in the actual knotting operation, a knotter hook 32 (Figs 2 and 8) is retracted axially inward (to the left as viewed in Fig. 8) and is simultaneously rotated in a counterclockwise direction, through substantially a full turn and a half. In the course of this retractive movement the hook 32 engages the bight of the reserve thread *a* and the rotation of the hook twists the thread so as to form the main loop *a*₁ for the final knot with the twisted portion *a*₂ at the base of this loop, which is utilized in obtaining the subsequent configuration of the threads as shown in Fig. 1^a described above. The end *a*₂ of the reserve thread is gripped by the upper shear clamp 10 while the standing part *a*₂ of this thread passes over a vertically shiftable finger 33 and through the lower clamp 11. The upper clamp 10 is timed to close at the end of this retractive and rotative movement of the hook 32 while the lower clamp 11 closes just slightly later (see time chart, Fig. 13). Consequently, ample slack is available for the looping and twisting of the thread by the hook 32 during the hook movement just described.

25 35 Before proceeding to the next step in the knotting operation, attention may be given to the actuating mechanism for the knotter hook 32 (Figs. 2, 3 and 4). In this particular arrangement, the hook 32 is carried on the outer end of a rotatable and axially shiftable shaft 34, which is suitably journaled in the frame of the mechanism. Axial shifting of the shaft 34 is effected by means of an oscillatable lever 35 (Fig. 4) pivoted intermediate its ends at 36 and having a cam follower roller 37 on its inner end which rides in a cooperating cam groove in one end face of the actuating cam 13. A segment of teeth 38 on the opposite end of the lever 35 mesh with teeth 39 on the shaft 34, which may be conveniently spirally formed. 40 45 Thus, as the lever 35 is oscillated by the rotation of the actuating cam 13, the knotter hook shaft 34 will be shifted axially in proper timed relation to the actuation of the other parts of the mechanism. Similarly, rotative movement of the hook shaft 34 is accomplished by means of a lever 40 (Fig. 3) pivoted intermediate its ends at 41 and having a cam follower roller 42 on one end thereof which is received in a complementary cam track groove in the side face of the actuating cam 13. For the sake of compactness it is desirable to accomplish the necessary rotation of the hook shaft 34 through its full turn and a half with a minimum of throw for the lever 40 and consequently a motion multiplication connection is provided between the lever 40 and the shaft 34. This connection includes a segmental series of teeth 43 on the free end of the lever 40 which mesh with a pinion 44. Fast on this pinion 44 is a segment of teeth 45 of larger radius than the pinion and which in turn mesh with an elongated pinion 46 fixed on the shaft 34. In this way rotation of the knotter hook 32 on the end of the shaft 34 is also effected in timed relation of the actuation of the other knotter mechanism elements.

60 65 70 75 In the second principal step of the knotting

operation the knotter hook 32 is utilized to form a temporary loop in one of the strands forming the main loop a_1 in the reserve thread a , and to draw this temporary or second loop through the main loop. To pull the loop a , over to the side of the shank of the hook 32 opposite the point of the hook, the knotter post or pin 30 is shifted laterally toward the reserve thread a from the position of Fig. 8 to that of Fig. 9. The initial portion of this lateral shift of the knotter post 30 serves to finally close the lower clamp 11, as was previously described. During the lateral shift of the knotter post 30 just described, the slack hook 12 is moved outwardly slightly to provide sufficient slack in the thread as it is pushed transversely by the knotter post (see time chart Fig. 13).

After the knotter post 30 has been shifted a sufficient distance to clear the knotter hook 32, the latter is projected outwardly to the position of Fig. 9 so that the main loop a_1 rides up on the shank of the hook. Furthermore, during the advancing movement of the hook 32 the finger 33 is elevated from its position shown in Fig. 8 to the dot-dash line position shown in Fig. 9 and then quickly dropped again to the full line position shown in Fig. 9. In this way the standing part a_2 of the thread a is dropped over the end of the hook 32. Thereafter the hook 32 is rotated in a clockwise direction through substantially 180°, or a half turn, so that its nose can pass through the main loop a_1 (Fig. 10). Finally, the knotter hook 32 is withdrawn to the position of Fig. 11, thereby drawing a second or temporary loop a_5 through the main loop a_1 . It should also be noted that in the course of this retractive movement of the hook 32 that it is re-rotated through substantially 180° in a counterclockwise direction so that the strands making up the loop a_5 will not be crossed.

At this point in the knotting operation (Fig. 11) the reserve thread a is looped in what is in effect a loose bowknot except that the strands of the main loop a_1 of the knot are twisted through a full turn and a half rather than merely through a half turn as in a conventional bowknot. The temporary loop a_5 constitutes, of course, the bow 40 of the bowknot.

Insertion of the second or exhausted thread b into the temporary second loop a_5 in the reserve thread a , constitutes the third main step of the knotting operation. For this purpose an exhausted thread hook 47 is projected laterally through the temporary loop a_5 to the dot-dash line position shown in Fig. 11 in which it engages a bight in the exhausted thread b which is presented to the knotter at the proper time by a down-take arm (not shown) like that of said Peterson patent. Thereupon the hook 47 is retracted and draws with it a bight of the exhausted thread b through the loop a_5 . This bight of the exhausted thread b is gripped between the hook 47 and a cooperating shearing clamp plate or jaw 48 so that the exhausted thread is sheared off at this point and held with the thread extending through the temporary loop a_5 in the reserve thread (Fig. 11).

In the fourth main step of the knotting operation, the temporary loop a_5 in the reserve thread is pulled back through the main loop a_1 so as to dissolve this temporary loop and at the same time draw the reserve thread b through the main loop a_1 and leave the exhausted thread loop extending about the standing part a_2 of the reserve thread. To this end, the knotter hook 32 is thrust outwardly again past the post 30 so as to free the temporary loop a_5 from it, and coin- 70 75

cidentally tension is applied to the standing part a_2 of the reserve thread by the slack take-up hook 12. This amounts, of course, to applying tension to the running strand of the bow for the temporary bowknot described above. In this way, the standing part a_2 of the reserve thread is drawn back through the main loop a_1 bringing with it the exhausted thread b so that the threads occupy substantially the configuration shown in Fig. 12. 5 Upon reference to this latter figure, it will be seen that the threads have now been looped in a modified form of loose weaver's knot substantially like that of Fig. 1*. The ends a_3 and b_3 of the reserve and exhausted threads are clamped as is the standing part b_2 of the exhausted thread. The standing part a_2 of the reserve thread a is also clamped and in addition tension is being applied to it by the slack knot 12 which has a further retractive movement at this point (see time chart Fig. 13).

In the fifth and final step of the knotting operation, the loops forming the knot are drawn tight and as an incident to such tightening of the knot the twisted portion a_4 of the reserve thread is drawn through the loop b_1 in the exhausted thread so that in the completed knot 25 the threads will have the configuration of the novel doubly interlocked knot shown in Fig. 1. For this purpose the tension on the standing part a_2 of the reserve thread is continued while the knotter post 30 is shifted axially downward to slip it free from the knot. It should be noted that this step of drawing a twisted portion of one thread within a loop in the other is wholly 30 35 novel and finds no counterpart in the conventional weaver's knot.

Opening of the clamps 10 and 11 releases the reserve thread a at the completion of the knotting operation described above. The upper clamp 10 is actuated directly from the cam 13, just as in the case of the corresponding clamp in said Peterson patent heretofore noted, and is opened at the end of the described knotting operation by an actuating arm which is shifted 45 by the cam 13. The lower clamp 11, however, is opened, in the present case, by a further and extreme lateral shift of the knotter post 30 to the position of Fig. 5c. In the course of such lateral movement of the post 30 the link 27 is pulled upwardly (as viewed in Fig. 5b) and the pin 26 rides along the outer end face of the cam plate 25. As a result, the pin 26 oscillates the clamp plate 17 in a clockwise direction (as viewed in Fig. 5b) so that the clamp finger 15, 50 55 on the plate 17, is swung to its full open position (Fig. 5c). When the knotter post 30 comes to rest in its extreme laterally shifted position the pin 26 is seated in the upper end of the slot 28, with the clamp plate 17 and link 27 in the 60 65 positions of Fig. 5c. The arrangement of the parts is such that the clamp 11 will remain open during the time that the arm 20, which carries the cam plate 25 and slack hook 12, returns to its initial position (Fig. 5). As the arm 20 rises, the curved outer end face of the cam plate 25 rides past the pin 26 without changing the latter's position. Similarly, upon the subsequent descent or return lateral movement of the knotter post 30, the pin 26 rides down the groove 28 and without shifting the angular position of the clamp plate 17 about its pivot pin 18. The friction of the compression spring 19, which encircles the pin 18, is sufficient to overcome the friction of the pin 26 in the slot 28, during the descent of the pin 26 just noted, so that the 70 75

clamp plate 17 remains immobile in its open position. As a result the parts all finally return to their initial positions shown in Fig. 5. In this same connection it will be noted that at a much earlier point in the cycle (see the time chart, Fig. 13) the clamp 11 also remains closed even though the knotter post 30 is returned from its intermediate position (shown in Fig. 5b) to its initial position (shown in Fig. 5). The clamp plate 17 remains immobile during this intermediate return motion of the knotter post 30 since the pin 26 rides down the slot 28 and again the spring 19 prevents angular movement of the clamp plate 17 which would otherwise be caused by the friction of the pin 26 on the edges of the slot 28.

A difference in the tension placed on the reserve thread *a*, by the slack drawing hook 12, is desirable in different portions of the knotting operation. In particular, during the initial drawback of the knotter hook 32 the thread is in a position to withstand a substantial tension exerted by this knotter hook and the tensioning hook 12. Near the end of the knotting operation, however, when the hook 12 is retracted still further, to complete the drawing tight of the knot, the thread is not positioned to withstand tensioning so well. Accordingly, means has been provided in which two springs, or similar yieldable biasing members, are arranged so that slack is drawn against the resistance of both of these springs during the first period mentioned and against the resistance of only one spring during the second period.

In the particular thread tensioning construction illustrated (Fig. 7), the plate 24 is pivoted on a pin 49 carried by a bracket 50. As the slack hook 12 descends it draws the reserve thread *a* across the projection 23 on the plate 24 so that the latter tends to swing in a counterclockwise direction (as viewed in Fig. 7). Swinging of the plate 24 in this direction is yieldably resisted by a pair of contractile springs 51 and 52. The spring 51 is anchored at its outer end to a projection 53 on a fixed plate 54, which carries the bracket 50. Similarly, the inner end of the spring 51 is anchored to an arm 55 integral with the plate 24. It should be noted at this point that the arm 55 is notched as indicated at 56 so that the point of attachment for the spring 51 may be varied at will with a consequent change in the length of the moment arm about the pivot pin 49 through which the spring acts and, hence, a corresponding change in the biasing torque exerted by the spring on the plate 24.

The second biasing spring 52 has an indirect connection with the swingable plate 24 so that it is operatively connected thereto during only a portion of the period occupied by the complete knot tying operation. In particular, the outer end of the spring 52 is anchored to the fixed plate 54 by a pin 57. The inner end of the spring 52 is, however, anchored to an intermediate plate 58 pivoted by a pin 59 on the fixed plate 54. An abutment 60 on the pivoted plate 58 underlies the plate 24 so that during its downward motion the plate 24 strikes the abutment 60 and swings the pivoted plate 58 in a direction to tension the spring 52. A second abutment 61 is provided on the plate 58, however, and is located in the path of a part 12a of the descending slack drawing hook 12 (Fig. 7). Consequently, when the latter approaches its lower extremity of movement it strikes the abutment 61 and swings the abutment 60 out of contact with the plate 24, 75

thereby interrupting the operative connection between the spring 52 and plate 24. Upon reference to the time chart (Fig. 13) it will be seen that this extreme motion of the slack drawing hook 12 takes place at a time close to the end of the knotting operation and during which the slack drawing hook is pulling the thread *a* to draw the loops of the knot tight and complete the same. By virtue of the arrangement described it will be seen that only the single spring 51 acts on the plate 24 during this final tensioning operation so that the tensioning force exerted on the reserve thread *a* is substantially diminished as compared to that in the initial knot tying operation during which both of the springs 51 and 52 act simultaneously to tension the reserve thread. The amount of tension provided for drawing the knot tight may be adjusted with nicety by changing the setting of the spring 51 so as to conform with the tensile characteristics of the particular type of thread or yarn being knotted.

In summary of the knotting operation, it will be seen that in general the threads are arranged as shown in Fig. 1a and then drawn tight to the final knotted arrangement of Fig. 1. In this final operation the twisted portion *a*₂ of the thread *a* is pulled within and squeezed by the main loop *b*₁ in the thread *b*. In this way a doubly interlocked knot of extreme strength is formed. Preferably the threads are preliminarily arranged (in the configuration of Fig. 1a) for this important final step described above, by first forming a doubly twisted main loop *a*₂ in one thread *a* (Fig. 8), completing a temporary bowknot by drawing a bow or loop *a*₃ through the main loop (Fig. 11), inserting a second thread *b* through the bow *a*₃ (Fig. 11), and then tensioning the running strand *a*₂ of the bow so as to dissolve the bow and withdraw the thread *b* through the main loop *a*₁ (Fig. 12). The continuation of tension in the strand *a*₂, and withdrawal of the knotter post 30, achieves the final transformation step in which the threads shift position from that of Fig. 12 to that of Fig. 1, through the intermediate stages shown in Figs. 1a and 1b. In the completed knot (Fig. 1), the portion *a*₄ of the thread *a* is encircled and squeezed by the loop *b*₁ to accomplish an extra interlock between the threads in addition to the interlocking loops and strands of an ordinary weaver's knot. By virtue of this added interlock, a doubly interlocked knot is achieved which effectually unites even such springy material as wool strands.

Although a particular embodiment of the invention has been shown and described in some detail, there is no intention to thereby limit the invention to such embodiment and application, but on the other hand, the appended claims are intended to cover all other modifications within the spirit and scope of the invention.

I claim as my invention:

1. The method of knotting together a pair of threads, which comprises, looping the threads together in the form of a loose weaver's knot of conventional configuration for such a knot except that the end of one thread, which normally in a standard weaver's knot projects between a portion of the same thread and the strands of a loop formed in the other thread, is instead twisted about said portion of the same thread and projects free of said other thread; and then drawing the knot tight and as an incident to such tightening drawing said twisted portion of said one thread through the loop in said other thread so that it is encircled and gripped by such loop.

2. The method of knotting together a pair of threads, which comprises, tying what generally resembles a loose single bowknot in one of the threads but in which knot the strands at the base of the main loop, through which the bow projects, are twisted about each other through substantially a full turn and a half; inserting a second thread through the bow; tensioning the running strand of the bow to withdraw the bow through said main loop along with the second thread, which is inserted through it; and continuing the tensioning of such running strand until the final knot is drawn tight with the twisted strands at the base of the main loop encircled by a loop in the second thread.

3. The method of knotting together a pair of threads which includes the preliminary looping together of the threads in a modified form of weaver's knot by first forming what generally resembles a loose single bowknot in one of the threads but in which knot the strands at the base of the main loop, through which the bow projects, are twisted about each other through substantially a full turn and a half; then inserting a second thread through the bow; and tensioning the running strand of the bow to dissolve the bow and draw the second thread through said main loop with the second thread itself looped about one of the strands of such main loop.

4. A method of knotting together two threads in which, the threads are preliminarily arranged with oppositely projecting loops formed in the respective ends of the threads and with the standing part of one thread extending through the loop in the other thread while the end of said one thread is twisted about said standing part and projects freely of said last named loop, and with both the standing part and one end of said other thread projecting through the loop in said one thread, and then drawing the knot tight after such preliminary configuration of the threads and in such latter operation pulling said twisted portion of said one thread through the loop in said other thread.

5. The method of knotting together a pair of threads which comprises, forming a main loop in one thread with the strands constituting the loop twisted through substantially a turn and a half at the base of the loop, then forming a second loop in a standing part of the thread adjacent the main loop and drawing it through the main loop from the side of the latter opposite said standing part in which said second loop is formed, inserting a second thread through the second loop thus formed, withdrawing the second loop together with the inserted second thread, whereby to dissolve said second loop and to form a third loop in said second thread encircling one of the standing parts of the first thread, and applying a tensioning force to said last named standing part of said first thread to draw said twisted base portion of said main loop through said third loop as an incident to the final tightening of the knot.

6. The method of knotting together a pair of threads, which comprises, forming a main loop in one thread with the strands constituting the loop twisted through substantially a turn and a half at the base of the loop, then forming a second loop in a standing part of the thread adjacent the main loop and drawing it through the main loop from the side of the latter opposite said standing part in which said second loop is formed, inserting a second thread through the

second loop thus formed, and withdrawing the second loop together with the inserted second thread, whereby to dissolve said second loop and to form a third loop in said second thread encircling one of the standing parts of the first thread.

7. A knotter comprising, in combination, means for forming a loose single bowknot in a first thread but with the strands of the main loop twisted through substantially a full turn and a half, means for inserting a second thread through the bow of the knot formed by said first named means, and means for tensioning the running strand of the bow to withdraw the bow through the main loop of the bowknot along with the second thread inserted through it and finally to pull the twisted base portion of the main loop within the resulting loop in the second thread as an incident to drawing tight the completed knot.

8. A knotter comprising, in combination, means for forming a loose single bowknot in a first thread but with the strands of the main loop twisted through substantially a full turn and a half, means for inserting a second thread through the bow of the knot formed by the first named means, and means for tensioning the running strand of the bow to dissolve the bow and draw the second thread through the main loop with the second thread itself looped about one of the strands of such main loop.

9. A knotter comprising, in combination, means including a rotatable hook engageable with a bight in a first thread for forming a loop in such thread with the strands at the base of the loop twisted through substantially a first turn and a half, means for positioning one of the twisted strands for engagement by the hook to form a second loop in said one thread extending through the first loop, means for inserting a second thread through the second loop, and means for tensioning one of the strands of the first thread to draw the twisted base portion of the first loop within a loop formed in the second thread as an incident to the withdrawal of the second thread and the second loop through the first loop.

10. A knotter comprising, in combination, means for looping a thread with the strands of the loop twisted about themselves and for drawing one of the strands through the loop in the manner of a bow in a bowknot, means for inserting a second thread through the bow, and means for tensioning the running strand of the bow to dissolve the latter and to pull the second thread into a loop interlocked with a strand of the main loop and finally to draw the twisted portion of the first thread within the loop in the second thread as an incident to completion of the tightening of the knot.

11. A knotter comprising, in combination, means for intertwining a pair of threads in the form of a knot, means for tensioning at least one of said threads during a plurality of periods in the knotting operation of said first named means, and means operable in timed relation to the first named means for varying the tensioning force produced by the second named means.

12. A knotter comprising, in combination, means for intertwining a pair of threads in the form of a knot, means including a pair of relatively movable tensioning members adapted to receive at least one of the threads therebetween to tension the same by relative movement between said members, means including a pair of yield-

able resilient members for resisting movement of one of said tensioning members, and means responsive to a predetermined relative movement between said tensioning members for rendering at least one of said resilient members ineffective thereafter to resist movement of said one tensioning member.

13. A knotter comprising, in combination, means for intertwining a pair of threads in the form of a knot, a pivoted plate arranged to have at least one of the threads led over an edge thereof, a hook at one side of said plate disposed to move past the adjacent plate face to tension such thread by pulling it across said plate edge, said plate being movable about its pivot in the direction of hook movement, means including a plurality of springs for yieldably biasing said plate to swing about its pivot in a direction to tension the thread, and means responsive to a predetermined movement of said hook in one direction for rendering at least one of said springs ineffective to bias said plate during further movement of said hook in said one direction.

14. A knotter comprising, in combination, means for intertwining a pair of threads in the form of a knot, a pivoted plate arranged to have at least one of the threads led over an edge thereof, a hook at one side of said plate disposed to move past the adjacent plate face to tension such thread by pulling it across said plate edge, said plate being movable about its pivot in the direction of hook movement, means including a pair of springs for yieldably biasing said plate to swing about its pivot in a direction to tension the thread, means responsive to a predetermined movement of said hook in one direction for rendering one of said springs ineffective to bias said plate during further movement of said hook in said one direction, and means for adjusting the torque applied to said plate by the other spring.

15. A knotter comprising, in combination, means for intertwining a pair of threads in the form of a knot, a pivoted plate arranged to have at least one of the threads led over an edge thereof, a hook at one side of said plate disposed to move past the adjacent plate face to tension such thread by pulling it across said plate edge, said plate being movable about its pivot in the direction of hook movement, a spring for yieldably biasing said plate to swing about its pivot in a direction to tension the thread, a second member pivoted for movement about an axis coincident with that of said plate, said plate and second member being fashioned with portions engageable upon movement of said plate in a direction to relieve the tension in the thread, a second spring for biasing said second member for movement in a direction to cause engagement of it with said plate and to swing the latter to tension the thread, and means including interengaging portions of said hook and second member for causing the hook to move said second member out of engagement with said plate after a pre-

determined movement of said hook in a thread tensioning direction.

16. In a knotter mechanism embodying a laterally shiftable knotter post and a movable slack drawing member, the combination of a thread clamp comprising a pair of relatively movable clamping jaws, and means responsive to movement of the slack drawing member for shifting said jaws relatively to each other from a full open position to an intermediate although still open position, said last named means being responsive to a lateral shift of the knotter post for closing said jaws from such intermediate position.

17. In a knotter mechanism embodying a laterally shiftable knotter post and a movable slack drawing member, the combination of a thread clamp comprising a pair of relatively movable clamping jaws, and means responsive to the movement of the slack drawing member for shifting said jaws relatively to each other from a full open position to an intermediate although still open position, said last named means being responsive to an initial lateral shift of the knotter post in one direction for closing said jaws from such intermediate position and responsive to a further shift of the knotter post in the same direction for reopening said jaws.

18. In a knotter mechanism the combination with a movable knotting device engageable with a thread to be tied, of a thread clamp comprising a pair of relatively movable clamping jaws, and means responsive to a movement of said device in one direction for closing said jaws and responsive to a further predetermined movement of said device in the same direction for reopening said jaws.

19. In a knotter mechanism the combination with a movable knotting device engageable with a thread to be tied, of a thread clamp comprising a pair of relatively movable jaws, means responsive to a movement of said device in one direction for closing said jaws and responsive to a further predetermined movement of said device in the same direction for reopening said jaws, and means for retaining said jaws in their reopened position during a return of said device to its initial position.

20. In a knotter mechanism the combination of, a laterally shiftable lever having a knotter post mounted thereon, a movable slack drawing device, an actuator arm for said device, a fixed thread clamping jaw and a cooperating pivoted jaw having a slot therein, a pin in said slot, means on said actuator arm for camming said pin in a direction to pivot said movable jaw toward closed position in response to movement of said actuator arm, and means including a link pivoted at one end on said lever and carrying said pin on the other end for pivoting said movable jaw still further and into fully closed position in response to a lateral shift of said lever carrying said knotter post.

HARRY G. LIND.
